UNITED STATES PATENT OFFICE.

SOLOMON GERMAN, OF HALETHORPE, MARYLAND.

CORN-HUSKING MACHINE.

1,273,355.

Specification of Letters Patent. Patented July 23, 1918.

Application filed December 22, 1916. Serial No. 138,385.

To all whom it may concern:

Be it known that I, SOLOMON GERMAN, a citizen of the United States, residing at Halethorpe, in the county of Baltimore and 5 State of Maryland, have invented certain new and useful Improvements in Corn-Husking Machines, of which the following is a specification.

This invention relates to machines for removing the husks from ears of corn, and it 10 is an improvement in the machines disclosed in my Patents Nos. 1,176,359 and 1,194,615, dated March 21, 1916, and August 15, 1916, respectively.

15 The invention has for its object to provide a novel and improved mechanism whereby the husks are expeditiously and thoroughly removed from the ears.

The invention also has for its object to 20 provide a portable machine of the kind stated which can be operated in the field, and which is provided with means whereby it may be leveled up when standing on a hill-side.

25 The objects stated are attained by means of a combination and arrangement of parts to be hereinafter described and claimed, and in order that the same may be better understood, reference is had to the accompanying drawings, forming a part of this specification.

In the drawings—

Figure 1 is a side elevation of the machine;

35 Fig. 2 is a plan view thereof;

Fig. 3 is a rear end view;

Fig. 4 is an elevation of a husk-stripping mechanism, with parts in section;

Fig. 5 is an elevation showing certain 40 gears of the said mechanism;

Fig. 6 is an enlarged horizontal section on the line 6—6 of Fig. 4;

Fig. 7 is a cross-section on the line 7—7 of Fig. 6;

45 Fig. 8 is a sectional detail showing a leveling device;

Fig. 9 is a sectional detail showing a modified form of stripping mechanism;

Fig. 10 is a horizontal section on the line 50 10—10 of Fig. 9, and

Figs. 11 and 12 show further modifications of the stripper mechanism.

Referring specifically to the drawings, the mechanism is mounted on a truck so that

it may be conveniently hauled from place 55 to place and operated in the field. However, it will be understood that the machine may be built stationary, but it is preferably made portable. The truck has front and hind wheels 1 and 2, respectively. The front 60 wheels are carried by a frame 1^a and they are swiveled to said frame so that the truck may be steered. The hind wheels are carried by an axle 2^a on which is mounted a bearing 3 for a reach 4 connecting said axle 65 with the frame 1^a. These parts form the running gear of the truck and support a suitable frame work 5 on which the husking mechanism is mounted. This truck frame is pivotally mounted on the reach 4 so that 70 it may be tilted laterally to level the machine when it is standing on a hillside. The front end of the frame is pivoted to the corresponding end of the reach 4, and the rear end of the frame is pivotally connected 75 to the corresponding end of the reach. In order that the truck frame may be tilted to level the machine, there is connected to the axle 2^a an upstanding stem 6 said stem being pivoted, as shown at 6^a, to a bracket 80 6^b fixed on said axle. The upper end of this stem is screw-threaded and passes through a nut 7 rotatably supported in a bearing 7^a fixed to a member 7^b of the truck frame. A bevel gear 8 is fixed to the nut 7 85 and with said gear meshes a bevel gear 8^a on a shaft 9 suitably supported on the truck frame and provided with a hand wheel 9^a. It will be seen that when the shaft 9 is rotated by operating the hand wheel, the nut 7 is turned through the bevel gears 8 and 8^a, and as said nut travels on the stem 6, the truck frame is tilted to either side of 90 its axis, the latter being the reach 4, and the tilting mechanism being on one side of 95 this axis.

The frame of the truck supports a suitable engine or motor 10 which drives the husking mechanism and other devices to be presently described, the same being also 100 supported in working position on the truck frame. The stalks from which the ears are to be removed and husked are taken up by a conveyer 11 and deposited on a table 12 where they are grasped by the operator and presented to a rotary cutter in the form of a circular saw 13 to sever the ears from the stalks. The saw is on a shaft 14 which is 105

belted or otherwise operatively connected, as indicated at 14^a, to a countershaft 15, which latter, in turn, is operatively connected by a belt 15^a, or otherwise, to the shaft 5 of the engine 10. The shaft 11^a of the conveyer 11 is driven from the countershaft 15 by a chain, belt, or other suitable means 11^b. Associated with the saw 13 is an auxiliary cutter 13^a similar to the one described 10 in my Patent No. 1,194,615, dated August 15, 1916.

After the ears are severed from the stalks, the former pass to the husking mechanism. The stalks and husks will be tied into bundles, a suitable bundling mechanism 16 15 driven by a chain, belt, or other suitable means 16^a from the shaft 15.

The husking mechanism comprises the following parts:

20 Below the table 12, adjacent to the cutter 13, is mounted a housing 17 into the upper open end of which the ears are thrown to be operated on by the husking devices in the housing. The upper inlet end of the 25 housing contains a hopper 17^a which centers the ears and guides them to the husking mechanism.

Below the hopper 17^a, the housing 17 contains two vertically spaced pairs of feed 30 rollers 18 and 19, respectively, which are peripherally grooved, the ears being fed by passing between said grooved portions of the rollers.

The two upper feed rollers 18 are mounted 35 on shafts 18^a, and each of these rollers is pivotally supported so that they are free to swing toward and from each other. This pivotal support is obtained by supporting the shafts 18^a on swinging arms 20 supported by a shaft 21. Two arms are provided 40 for each roller, the latter being located between the arms, and the arms being fixed to a sleeve 21^a mounted loosely on the shaft 21 so that it may turn freely thereon. The 45 two arms therefore swing together and the roller carried by the arms is made to swing straight and uniformly at each end without a lateral deviation.

On the shafts 18^a and 21 are meshing 50 gears 22 and 22^a, respectively, whereby the motion of the latter shaft is transmitted to the former, and the roller 18 carried thereby is driven. The shaft 21 obtains motion from a vertical shaft 23 located outside the housing 17, a worm gearing 23^a between said shafts being provided.

Both rollers 18 are supported and driven in the manner hereinbefore described and the supporting arms 20 of said rollers are connected by a coiled spring 24 tending to draw the rollers together. The rollers therefore yield to allow ears of different diameters to pass therebetween, and they grip the ears and feed the same downward in the 65 housing 17.

The shaft 23 drives both rollers 18, its worm wheel meshing with worm wheels on the respective drive shafts 21 of the rollers.

The shaft 23 obtains motion from the countershaft 15 through a bevel gearing 24. 70

The lower pair of feed rollers 19 is supported in the same manner as the upper pair 18, a similar drive gearing being also employed.

Between the upper and lower feed rollers 75 18 and 19, the housing 17 contains a device for stripping the husks from the ears. This device is a rotary brush consisting of a hollow cylinder or ring 25 on the inside of which are fixed the bristles 25^a. The brush 80 cylinder is carried on the inside of a ring 26 which is toothed to form a spur gear. The housing 17 carries suitable bearings 27 supporting the gear 26, and in mesh with said gear is a gear 28 on the shaft 23, whereby the brush is driven.

Associated with the stripper brush hereinbefore described is a cutter for slitting the husks to facilitate their removal from the ears. This cutter comprises a series of 90 knives 29 pivoted at one end, as shown at 29^a, to an annular plate 30 mounted on top of the brush cylinder 25. The free outer ends of the knives project over a sufficient distance from the inner periphery of the 95 brush cylinder to come in contact with the outside of the ears about to pass therethrough, and they are held yieldingly pressed outward by springs 31. As the knives are carried by the rotary brush, they 100 revolve with the same, and they are set horizontally to cut transversely of the ears. It will therefore be seen that when the ears are fed forward in the direction of their length past the knives, the husks are 105 cut into spiral strips which are readily removed from the ears by the rotating brush. The upper feed rollers 18 push the ears downward through the stripping mechanism, and the lower feed rollers 19 pull the 110 ears downward through said mechanism. The husks stripped from the ears are removed from the bottom of the housing by an air suction apparatus comprising a fan 32 having its suction pipe 32^a connected to 115 the housing. The fan is driven by a belt 33 from the countershaft 15.

Figs. 9 and 10 show a modified arrangement of cutters for slitting the husks as the ears pass to the rotary brush 25. The 120 knives 34 in this instance are not carried by the brush, but are independently supported by a shelf 35 mounted in the housing 17, said shelf having a central opening 35^a in line with the interior of the brush, 125 and the knives depending from the shelf and being grouped in a circle around the opening. The knives are mounted vertically to swing in a vertical plane transversely of the path of movement of the ears, 130

and they are pivoted to the shelf as indicated at 36. Springs 36^a are also provided for holding the knives yieldingly in cutting contact with the outside of the ears. The lower cutting portions of the knives are somewhat hook-shaped, the hook pointing inward.

Fig. 11 shows a modified form of husk-stripping brush. This stripper consists of a group of rotary brushes 37 which are substituted for the brush 25. The brushes have their axes arranged vertically and parallel, and they are set to form a vertical space down which the ears are fed. Any suitable drive gearing may be provided for operating the brushes.

Another modified form of stripper brush is shown in Fig. 12. This brush comprises a series of segments 38 pivoted at 38^a to a rotatable member 39. The segments are arranged in a circle around a central opening 39^a in the member 39 through which the ears pass, and they are held pressed inward by springs 40. Husk-stripping knives as hereinbefore described may or may not be used as is found expedient, in conjunction with this form of brush.

I claim:

1. In a corn husking machine, a hollow rotary brush, means for feeding the ears lengthwise through the brush, and a series of husk cutting blades carried by the brush

at the entrance end thereof and having their cutting edges in the path of the ears.

2. In a corn husking machine, a husk stripping device comprising a rotary member having an opening through which the ears are adapted to be fed lengthwise, and a series of brushes carried by the member and encircling the entrance end of the opening, said brushes being pivoted, and means for yieldingly holding the brushes pressed inward into working position.

3. In a corn husking machine, a husk stripping mechanism, and a pair of feed rollers associated with said mechanism, shafts on which the rollers are mounted, a pair of swinging arms carrying each shaft, the rollers being mounted between the respective pairs of arms, sleeves to which the respective pairs of arms are fastened, shafts on which the sleeves are rotatably mounted, means for yieldingly holding the rollers pressed toward each other, a drive gearing between the roller shafts and the second mentioned shafts, and driving means for said second mentioned shafts.

In testimony whereof I affix my signature in the presence of two witnesses.

SOLOMON GERMAN.
